SECURITY DOOR HOLDER

Wylie S. Wilkison, Bayard, N. Mex.

Application August 17, 1945, Serial No. 610,912

7 Claims. (Cl. 292—341)

1

This invention relates to a door holder and it is one object of the invention to provide a door holder adapted to be applied to a door and a door frame and by means of which a door may be held open various degrees and prevented from being blown shut or open out of the desired position.

Another object of the invention is to provide a door holder so formed that it may be actuated with one hand and readily moved to secure or release the door.

Another object of the invention is to provide a door holder which, when applied to a door and a door frame for use, will not detract from the appearance of the door.

Another object of the invention is to provide a door holder which consists of a small number of parts and is quite simple in construction and may be manufactured at small cost.

The invention is illustrated in the accompanying drawings wherein:

Figure 1 is a view in elevation showing the improved door holder applied to a door and a door frame in position for use.

Figure 2 is a top plan view of Figure 1.

Figure 3 is a view taken along line 3—3 of Figure 1.

Figure 4 is a fragmentary sectional view taken along line 4—4 of Figure 1.

Figure 5 is a fragmentary top plan view of the door holder, an opened position of the door being indicated by dotted lines.

Figure 6 is a view in elevation of Figure 5.

Figure 7 is a fragmentary sectional view taken along the line 7—7 of Figure 6.

This improved door holder is applied to a door 1 and the upper portion of a door frame 2 and when so applied constitutes means for holding the door opened as far as desired and preventing the door from blowing shut.

A bearing bracket 3 is attached to the upper portion of the door frame 2 and has an ear 4 to which an arm or bar 5 is connected by a bolt 6. The arm or bar 5 projects from the door frame and through its outer end passes a bolt 7 carrying a circular block 8 having teeth about its peripheral edge face. The bolt 7 not only connects the block with the arm but also prevents the block from turning relative to the arm. The lower portion of the bolt projects downwardly from the block and passes through a slot 9 formed in a bar 10 longitudinally thereof. The bar 10 may therefore have sliding movement radially of the block and also pivotal movement about the bolt.

The bar 10 is shifted longitudinally in order to move the tooth 11 of a latch 12 into and out of

2

engagement with the toothed block or disc 8. This is accomplished by door-carried mechanism including rods 13 and 14. The shaft or rod 13 extends across the upper end of the door and slidably mounted through a bracket 15 carried by the door, the front end of rod 13 being pivoted to an arm 16 projecting outwardly from the upper end of shaft 14. The shaft or rod 14 extends vertically adjacent the free side edge of the door and has its lower portion rotatably mounted through a bracket 17 and terminating in a crank handle 18 by means of which it may be rotated and impart swinging movement to arm 16 for shifting the rod 13 longitudinally. A curved plate or strip 19 is secured to the door and extends transversely of rod 14 between the rod and the door and serves as a wear plate for the rod and also as a brake for preventing too free turning of the rod. The inner end of rod 13 is pivoted to the inner end of a link or lever 20 pivotally mounted between ears 21 of a bracket 22 by a pin 23, and this lever 20 carries an upstanding block or post 24 carrying an arm 25 at its upper end. The arm 25 projects outwardly from the block 24 and its outer end is pivotally connected with the inner or rear end of rod 13 by a pin 26. Shifting of the rod 13 longitudinally in one direction will cause the bar 10 to be shifted longitudinally in a direction to move the latch 12 away from the disc 8 and permit free opening or closing movement of the door. After the door has been moved to the desired position, the rod 14 will be turned by its handle 18 to shift the rod 13 longitudinally in the opposite direction and the latch will be moved into engagement with the toothed disc or keeper and the door will be securely held against movement out of the desired position of adjustment. Since the rods 13 and 14 extend parallel to and close to the marginal edges of the door, the device may be applied to doors having glass panels, and this arrangement of rods also disposes the rods and mechanism controlled thereby in such position that they will be inconspicuous and not detract from the appearance of the door.

What is claimed is:

1. A door holder comprising a mounting adapted to be mounted on a door frame above a door hinged at one side edge to the frame for swinging movement to opened and closed positions, an arm carried by said mounting and extending outwardly therefrom, a circular toothed block, a bar having a front end portion formed with a longitudinally extending slot and disposed across said block diametrically thereof, a

pin passing through the arm and the block and through the slot of said bar to slidably and pivotally mount the bar, a latch carried by said bar for engaging the teeth of said block, a bearing bracket adapted to be mounted on the door adjacent the hinged side edge thereof, a lever pivoted intermediate its length to said bracket, an upright member carried by the outer end of said lever, an arm extending outwardly from the upper end of the upright member and pivoted to the rear end of said bar, a rod pivoted at its rear end to the inner end of said lever, a bearing bracket for slidably mounting said rod horizontally across the upper portion of the door, an actuating rod disposed vertically and having an arm at its upper end pivoted to the front end of the first rod and a crank handle at its lower end, and a bearing bracket for rotatably mounting the actuating rod vertically along the free side edge portion of the door.

2. A door holder comprising a mounting adapted to be mounted on a door frame above a door hinged at one side edge to the frame for swinging movement to opened and closed positions, an arm carried by said mounting and extending outwardly therefrom, a circular toothed block, a bar having a front end portion formed with a longitudinally extending slot and disposed across said block diametrically thereof, a pin passing through the arm and the block and through the slot of said bar to slidably and pivotally mount the bar, a latch carried by said bar for engaging the teeth of said block, a bearing bracket adapted to be mounted on the door adjacent the hinged side thereof, a lever pivoted intermediate its length to said bracket and having its outer end connected with the rear end of said bar for shifting the bar longitudinally and moving its latch into and out of engagement with the toothed block, a rod extending horizontally and pivoted at its rear end to the inner end of said lever, and a vertically disposed rotatable rod having an arm connected with the front end of the horizontal rod for shifting the same longitudinally when the vertical rod is turned.

3. A door holder comprising a mounting adapted to be mounted on a door frame above a door hinged at one side edge to the frame for swinging movement to opened and closed positions, an arm carried by said mounting and extending outwardly therefrom, a circular toothed block, a bar having a front end portion formed with a longitudinally extending slot and disposed across said block diametrically thereof, a pin passing through the arm and the block and through the slot of said bar to slidably and pivotally mount the bar, a latch carried by said bar for engaging the teeth of said block, a bearing bracket adapted to be mounted on the door adjacent the hinged side edge thereof, a lever pivoted intermediate its length to said bracket and having its outer end connected with the rear end of said bar for shifting the bar longitudinally and moving its latch into and out of engagement with the toothed block, and actuating means for said lever adapted to be mounted on the door and including a rod connected with the lever for imparting pivotal movement to the lever.

4. A door holder comprising a bracket adapted to be mounted upon a door frame over a door hinged to the frame for opening and closing movement, an arm extending outwardly from said bracket, a block carried by said arm and having teeth, a bar extending across the block and mounted for sliding and pivotal movement, a

latch carried by said bar for engaging teeth of the block, a bearing bracket adapted to be mounted on the door, a lever pivoted to said bearing bracket, an upright member carried by said lever and having an arm at its upper end pivoted to said bar for shifting the bar longitudinally when the lever is swung about its pivot, a horizontal longitudinally shiftable rod pivoted at one end to said lever, and a vertically disposed rotatable rod having a turning handle at one end and its other end connected with the horizontal rod for shifting the same longitudinally when the vertical rod is turned.

5. A door holder comprising a mounting adapted to be mounted on a door frame over a door hinged for opening and closing movement, a toothed block carried by said mounting, a bar extending across the block slidably and pivotally mounted and carrying a latch for engaging the toothed block, a pin for mounting said block on said mounting and received in an elongated slot in said bar, a bearing bracket adapted to be mounted on the door, a member turnably carried by said bearing bracket and connected with the rear end of said bar for shifting the bar longitudinally when turned, and actuating means adapted to be mounted on the door and connected with the turnable member for turning the same and effecting shifting of the bar to move the latch into and out of engagement with said block.

6. A door holder comprising a mounting adapted to be mounted on a door frame over a door hinged for opening and closing movement, a toothed block carried by said mounting, a bar extending across the block slidably and pivotally mounted and carrying a latch for engaging the toothed block, a pin for mounting said block on said mounting and received in an elongated slot in said bar; a bearing bracket adapted to be mounted on the door, a lever pivoted to the bearing bracket and connected with said bar for shifting the bar longitudinally and moving the latch into and out of engagement with teeth of the block, a horizontal rod having its rear end pivoted to said lever, means for slidably mounting the horizontal rod, a vertically disposed rod having turning means at its lower end and an arm connecting its upper end with the front end of the horizontal rod, and means for rotatably mounting the vertical rod.

7. A door holder comprising a mounting adapted to be mounted on a door frame over a door hinged for opening and closing movement, a toothed block carried by said mounting, a bar extending across the block slidably and pivotally mounted and carrying a latch for engaging the toothed block, a pin for mounting said block on said mounting and received in an elongated slot in said bar; a bearing bracket adapted to be mounted against the door, a member turnably carried by said bearing bracket and connected with the rear end of said bar for shifting the bar longitudinally when turned, and actuating means for said turnable member.
